(57) CLAIM

The ornamental design for a recycling station, as shown and described.

DESCRIPTION

FIG. 1 is a top frontal perspective view of a first embodiment of a recycling station according to my new design;

FIG. 2 is a front view of the embodiment shown in FIG. 1;

FIG. 3 is a back view of the embodiment shown in FIG. 1;

FIG. 4 is a bottom view of the embodiment shown in FIG. 1;

FIG. 5 is a top view of the embodiment shown in FIG. 1;

FIG. 6 right side view of the embodiment shown in FIG. 1;

FIG. 7 is a left side view of the embodiment shown in FIG. 1;

FIG. 8 is a top frontal perspective view of a second embodiment of a recycling station according to my new design;

FIG. 9 is a front view of the embodiment shown in FIG. 8;

FIG. 10 is a back view of the embodiment shown in FIG. 8;

FIG. 11 is a bottom view of the embodiment shown in FIG. 8;

FIG. 12 is a top view of the embodiment shown in FIG. 8;

FIG. 13 right side view of the embodiment shown in FIG. 8;

and,

FIG. 14 is a left side view of the embodiment shown in FIG. 8.

The broken lines in the drawings are for illustrative purposes only and form no part of the claimed design.
